COMB CLEANER

Filed Dec. 7, 1928

Nell Fulton INVENTOR.

BY *Emile F. Lange*
ATTORNEY.

UNITED STATES PATENT OFFICE

NELL FULTON, OF NEW YORK, N. Y.

COMB CLEANER

Application filed December 7, 1928. Serial No. 324,541.

My invention relates to supports for comb cleaners of the kind consisting of webbing through which the teeth of the comb are drawn back and forth in the manner in which 5 a razor is stropped.

The primary object of the invention is to provide a support for the cleaner, the support being designed for the purpose of engaging both ends of the cleaner and being so constructed that it may readily be held by one hand while the comb is being drawn through it with the other hand.

Another object which I have in view is the provision of a support with means for ad- 15 justably tensioning the cleaner.

Still another of my objects is the provision of a support which holds the cleaner obliquely so that it is most effective when drawing the teeth of the comb through the cleaner.

20 It is also my object to provide a support for securely holding the cleaner during use but so constructed that the comb cleaner may be readily removed from the support when it is desired to wash the cleaner.

25 Having in view these objects and others which will be pointed out in the following description, I will now refer to the drawings, in which

Figure 1 is a view in perspective showing 30 one form of my comb cleaner.

Figure 2 is a perspective view showing a modified form of handle member.

Figure 3 is a view similar to Figure 1 but showing a wire frame support.

35 Figure 4 is a plan view of the cleaner shown in Figure 1.

The cleaner itself is shown at 10. This consists of a web having a plurality of strands through which the teeth of the comb 40 are drawn for cleaning purposes. The end portions 11 of the cleaner 10 are woven and are folded upon themselves and stitched to form loops. My invention consists of the elements of the support for holding the cleaner 45 10.

The support for the cleaner shown in Figure 1 includes a handle member 12 having a plurality of notches 13 and 14 for engaging the clips 15 and 16 respectively. The clip 50 15 has a horizontal member at its upper ex-

tremity for engaging the cleaner 10 through one of the loops and the extremity of the horizontal portion is bent outwardly to prevent accidental disengagement of the cleaner. The clip 15 is then bent at a rearward, down- 55 ward and inward inclination to engage the side of the handle member 12. From thence it passes across the under edge of the handle member and then rearwardly and upwardly and across the upper edge of the handle mem- 60 ber, its free end portion engaging the side of the handle member. The clip 16 is similar to the clip 15 except that the inclinations are all the reverse of those of the clip 15.

In applying the cleaner 10 to the support, 65 the clips are first caused to engage the support through the loops in the ends 11. The clips are both then caused to straddle the handle member 12 and a portion of the clip 15 is seated in the notch 13 of the handle 70 member 12. At this stage there will be considerable slack in the cleaner 10 but this slack may be taken up by moving the clip 16 to engage one of the notches 14. On a new cleaner the first notch will usually be found to give 75 the cleaner sufficient tension but after the cleaner becomes stretched, it becomes necessary to seat the clip 16 in one of the other notches 14.

The handle member shown in Figure 2 80 differs from that shown in Figure 1 only in the hand grip. In Figure 1 the handle member 12 is made sufficiently long to enable the user to grasp the handle member at 17, this being shaped for convenience in holding the 85 handle member. In the Figure 2 construction the handle member 12' has a hand grip 17' at the side, it being otherwise similar in all respects to the handle member 12 and including the notches 13' and 14'. The handle 90 members 12 and 12' may be made out of any suitable material, wood being perhaps the most satisfactory. The wood may be painted or enameled in any suitable color or metals or other materials may be substituted for the 95 wood when desired.

The support shown in Figure 3 differs somewhat from those shown in Figures 1 and 2 in that the support is formed entirely from heavy wire. The cleaner itself is shown at 100

10 and this is identical in all respects with the cleaner shown in Figure 1. The support consists of the two wire parts having the same function as the supports shown in Figures 1 and 2. One of the two wire parts 5 consists of a looped handle member 18 which is stepped downwardly at 19. One of the ends of this member is united with the other portion of the wire at 20 and the other portion of the wire continues rearwardly and is 10 then bent upwardly, outwardly and rearwardly at 21 and terminates in a horizontal portion for engaging the loop in the end of the cleaner 10. The other wire member has 15 a horizontal portion for engaging the rear loop of the cleaner 10 and it then passes downwardly to the stepped portion 19, across the under side of the handle 18 and finally forwardly and over the parallel portions of the 20 first mentioned wire member. The manner of attaching the cleaner 10 to the support in Figure 3 is similar to that in Figures 1 and 2. When it is desired to remove the cleaner from the support it is necessary to depress the 25 clip 22 to cause it to disengage from the stepped portion 19.

In the Figure 1 construction the clips 15 and 16 are oppositely inclined so that in both 30 cases the tension of the cleaner 10 is exerted in a manner such that the clips are seated in the notches 13 and 14 respectively. The action in the Figure 3 construction is also such that the tension of the cleaner 10 causes the clip 22 to bear down on the support and 35 to thus give a yieldable tension. It should also be noted that the horizontal portions of the two clips have their free ends on opposite sides of the support. The tendency for the cleaner when under tension is to 40 draw back on the free end of the horizontal portion. By positioning these horizontal portions in the manner shown, they will always remain parallel and oblique to the longitudinal axis of the handle. When the 45 comb is then drawn through the cleaner, the sides of the teeth are thoroughly scoured thus resulting in a more effective cleaning of the teeth.

Having thus described my invention in 50 such full, clear, and exact terms that its construction and operation will be readily understood by others skilled in the art to which it pertains, what I claim as new and desire to secure by Letters Patent of the United 55 States is:

1. A support for comb cleaners, said support including a handle member and means for engaging the comb cleaner at opposite extremities thereof and in spaced relation 60 with said handle member, said means being adjustably connected with said handle member for adjustably tensioning the comb cleaner.

2. A comb cleaner comprising a plurality 65 of strands adapted to engage between the

teeth of a comb and having loop portions extending across the opposite ends of the strands for retaining the same in parallel relation when stretched, and supporting means for detachable engagement with the loops at the opposite ends of the strands and each having a supporting arm for threaded engagement through the loops, said arms extending through the loops in opposite directions.

3. A comb cleaner comprising a web portion having a plurality of strands and loops extending across the opposite ends of the strands, and spaced supports for the web, each support having a transversely extending arm and the arms of the supports extending in opposite directions for engagement through the loops at the opposite ends of the web.

In testimony whereof I affix my signature. 85
NELL FULTON.
